(57) **CLAIM**

The ornamental design for a trailer for proppant containers, as shown and described.

DESCRIPTION

FIG. 1 is an upper perspective view of [the] a trailer for proppant containers [showing] embodying my new design. FIG. 2 is a side elevation view [thereof] of the embodiment of FIG. 1;

FIG. 3 is an opposite side elevation view [thereof] of the embodiment of FIG. 1;

FIG. 4 is a front elevation view [thereof] of the embodiment of FIG. 1;

FIG. 5 is a rear elevation view [thereof] of the embodiment of FIG. 1;

FIG. 6 is a top plan view [thereof] of the embodiment of FIG. 1; and,

FIG. 7 is a bottom plan view [thereof] of the embodiment of FIG. 1.

[The features presented in broken lines are for environmental purposes only and form no part of the claimed design.] *The broken lines depict portions of the trailer for proppant containers in which the design is embodied that are not considered part of the claimed design.*
